UNITED STATES PATENT OFFICE

GEORGE H. PHELPS, OF WAREHOUSE POINT, CONNECTICUT

RADIATOR

Original application filed January 26, 1928, Serial No. 249,538. Divided and this application filed June 10, 1929. Serial No. 369,622.

In certain previous applications, particularly those of Murray and Bennett Nos. 203-437 and 203,438 (Patent No. 1,750,643, March 18, 1930), filed July 5, 1927, there is described 5 a radiator comprising a steam pipe or other heating element and a radiating structure of sheet metal applied thereto by means of supplementary straps welded to each other through the sheet metal.

10 In my application No. 249,538, filed January 26, 1928, there is described a radiator and a welded joint and method which are particularly useful in making such radiators. The present application is a division of my

15 application 249,538.

The accompanying drawings illustrate embodiments of the invention.

Fig. 1 is a side elevation of the end of a radiator;

20 Fig. 2 is a plan of the same;

Fig. 3 is a vertical section through one of the joints of Fig. 1;

Fig. 4 is a similar section through a joint of an alternative style of radiator;

25 Fig. 5 is a face view of an end of one of the straps;

Fig. 6 is a longitudinal section of the parts before welding;

30 Fig. 7 is a cross-section of the same on the line 7—7 of Fig. 6;

Fig. 8 is a view similar to Fig. 3 of an alternative construction;

Fig. 9 is a section on the line 9—9 of Fig. 8;

35 Fig. 10 is a section similar to Fig. 3 of an alternative construction;

Fig. 11 is a section similar to Fig. 6 illustrating a modification.

Fig. 1 illustrates the application to a steam pipe 1 of a radiating structure comprising metal sheets corrugated to form laterally extending fins 2, slightly oblique, and longitudinally extending portions 3 which are bent outwardly at intervals to form recesses 4 embracing the pipe 1 between them. The pipe 45 and the corrugated plates are preferably copper or aluminum or other metals or alloys of comparatively high electrical and heat conductivity.

The spot welding of such metals is almost or quite impracticable because of the rapid

conduction of the current and the heat from the points to be joined as well as the high electrical conductivity of the metal itself. This difficulty is avoided, according to the inventions of the above cited applications, 55 by the application of welding straps 5 of steel or ferrous metal, and the present invention provides an improved means for welding such straps. The straps are provided with recesses 6 which embrace the copper sheet around the pipe and are welded together to form joints indicated as a whole by the numeral 7 between the opposite straps 5 and extending through the plates 3.

According to my previous application the 65 sheets 3 and the straps 5 were pressed together between electrodes while passing a current so that the sheets became alloyed with or dissolved into the steel of the straps.

In applying the present improvement to 70 such radiators the sheets 3 are provided with holes through which portions of the straps extend and are welded to each other. Fig. 3 shows the plates 3 united by straps 5 with welded joints 7 passing through openings in 75 the plates. Fig. 4 shows a similar method of attaching a single copper plate 3 to a pipe 1. The copper plate is recessed at 4 to extend partially around the pipe. Steel straps 5 are placed in position and welded to each other at 7 through holes in the single copper sheet.

With this method the straps 5 need not be of steel. They may be of other metals, such as brass or even copper. Since during the 85 heating period the straps are nowhere in intimate contact with anything but the electrodes and each other (see Fig. 6), there is no reason why the straps cannot be made of any material which can be formed to the desired shape and which can be butt welded.

Figs. 5, 6 and 7 show the particular method of welding proposed. The straps are punched to form short tubular projections 8 and 9 with squared edges which make a butt 95 weld when pressed between electrodes and heated by the current. One of the tubular projections, 8, is provided with a flat face and the other with a conical point or pilot 11 which enters the other projection when the 100

parts are assembled. This serves to bring the projections 8 and 9 into correct alignment and to hold them so during the initial stages of the welding operation.

5 The point is so fine that it does not alter the shape of the main part of the projection nor alter the character of the weld as a true butt weld. The process, therefore, obtains the excellent and uniform welds characteristic of the butt method, and the abutting projections are made self-aligning in the welding machine by the lateral engagement of the point 11 in the opposite projection.

10 The methods described above may be used 15 also for uniting parts analogous to the steel straps to other parts analogous to the copper sheets without the inclusion of the pipe and in various other structures than radiators. For radiators (as well as other structures) 20 the straps and the welding projections which pass through the sheet or sheets may be variously shaped.

15 In Figs. 8 and 9, for example, the straps are in the form of half rings 12, the ends of 25 which are reduced and passed through openings in the sheets 3 and butt welded to form ties 13.

20 The same method of welding may be applied directly to the sheets, without the use 30 of supplementary straps. Fig. 10 shows such a construction with sheets 14 having recesses 15 which embrace the pipe 1, the sheets having 35 projections on their adjacent faces which are welded together to provide ties 16. This 40 involves a space between the opposed sheets which is determined by the regulating of the size of the projections and the take-up during the welding operation. Such a construction is particularly useful in making radiators with fins or other radiating structure of steel 45 or similar metal.

45 Fig. 11 is a section similar to Fig. 6 in which the projections 8 and 9 are simple tubular projections with squared ends abutting 50 against each other. This type of projection is used where other means are provided for holding the straps in proper register during the welding operation.

55 The projections may be of various shapes, sizes and locations according to the metal and the character of the work. And in the welding of two pieces to each other through a hole in one or more intermediate pieces, projections may be used on only one instead of both 60 of the two outer pieces.

65 For radiators, this style of joint has particular advantages over soldering, clamping and similar methods previously used for attaching fins or radiating structures to steam or hot water pipes or to electric heating elements. In the use of such radiators the alternate expansion and contraction of the heating element causes a great strain on the joints between the pipe and the radiating structure and may in time destroy the inti-

mate connection which is important in securing a rapid transfer of heat. Some such methods of uniting the heating elements and the radiating structure are also tedious and therefore expensive.

70 The joints of the present invention can be made, all or in large groups, at one machine operation so as to be quite economical. And they hold the parts together unyieldingly and at the same time stiffen the tubes and the radiating plates so as to permit the making of these of the desired thin metal and of such comparatively soft metals as the desired high conductive copper and the like.

75 There is a peculiar advantage also in the use of straps of steel (in which term I include ferrous metals generally) where the heating element or the radiating structure or both are of copper (in which term I include cuprous metals generally). The higher coefficient of thermal expansion of the copper results in a greater enlargement of the latter as the temperature is raised so that it expands to a greater extent than the steel and increases the intimacy of contact with the radiating structure and thus increases the conductivity of the joint.

80 The comparatively slight expansion of the steel will be within its elastic limit so that when the radiator is cooled the steel will return to its original dimensions and will grip the parts together with its original efficiency.

85 Radiators of this type are particularly useful for heating the air of a room. The heat 100 is transmitted through the corrugated plates to the adjacent air. The vertical passages provided by the corrugated plates form a sort of flue in which there is induced a comparatively high velocity of the heated air 105 so that it is rapidly circulated through the room and returned to the lower ends of such passages.

90 The same type of radiator may be used for 110 cooling the air by circulating cold brine or the like through the tube and may be used in refrigerating and similar apparatus for various analogous purposes.

95 The term "straps" is used herein to designate extra pieces of metal applied to the 115 sheet metal radiating structure, either in the form shown in which it embraces the radiating structure where the latter fits around the heating element, or in various other forms. And such straps may be used alone or in connection with other means for securing the parts together with a good heat conducting relation to each other.

100 Various modifications may be made by those skilled in the art without departing 125 from the invention as defined in the following claims.

105 1. A radiator comprising a heating element and a radiating structure of sheet metal applied thereto by means of supplementary 130

straps united directly to each other through openings in the sheet metal at points beyond the heating element so as to hold the parts in close heat conducting relation with each other.

5 2. A radiator comprising a heating element and a radiating structure of sheet metal applied thereto by means of supplementary straps having projections united to each other

10 through holes in the sheet metal.

3. A radiator comprising a heating element and a radiating structure of sheet metal applied thereto by means of supplementary straps having projections passing through

15 holes in the sheet metal and welded to each other.

4. A radiator comprising a horizontally ex-
20 tended heating element in combination with a radiating structure providing air flues ex-

25 tending in a substantially vertical direction enclosed at the sides, said radiating struc-
ture held in intimate contact by two addi-

30 tional straps placed around a portion of the radiating structure and secured one to the
25 other through openings in the radiating struc-
ture at points close to the heating element.

5. A radiator comprising a horizontally ex-
35 tended heating element in combination with a radiating structure providing air flues ex-

40 tending in a substantially vertical direction enclosed at the sides, said radiating struc-
ture held in intimate contact by two addi-

45 tional straps placed around a portion of the radiating structure and welded one to the
other through openings in the radiating struc-
ture at points close to the heating element.

6. A radiator comprising a heating element
40 and a radiating structure applied thereto by
means of supplementary straps united to each
other through openings in the radiating struc-
ture, the straps being of metal of a coeffi-

45 cient of thermal expansion which is less than
that of the heating element.

7. A radiator comprising a heating element
45 and a radiating structure of sheet metal ap-
plied thereto and recessed to embrace the

50 heating element and supplementary straps
engaging the recessed portions of said sheet
metal extending beyond the same and united

55 directly to each other through openings in
the sheet metal at points beyond the heating
element so as to hold the parts in close heat
conducting relation to each other.

In witness whereof, I have hereunto signed
my name.

GEORGE H. PHELPS.
